UNITED STATES PATENT OFFICE.

FREDERICK B. BARROWS, OF DULUTH, MINNESOTA, ASSIGNOR TO HIMSELF
AND WILLIAM M. SPALDING, OF SAME PLACE.

APPARATUS FOR OPERATING DREDGE OR EXCAVATOR BUCKETS.

SPECIFICATION forming part of Letters Patent No. 430,561, dated June 17, 1890.

Application filed August 7, 1889. Serial No. 319,976. (No model.)

To all whom it may concern:

Be it known that I, FREDERICK B. BARROWS, of Duluth, in the county of St. Louis and State of Minnesota, have invented a new and Improved Apparatus for Operating Dredge and Excavator Buckets, of which the following is a full, clear, and exact description.

The invention relates to hoisting-machines; and its object is to provide a new and improved hoisting-bucket specially designed to conveniently, rapidly, and automatically transfer coal, grain, and other similar articles from one place to another.

15 The invention consists of a carriage provided with a tail-carriage, a bucket held on a rope supported from the said carriage, and a bucket-boom provided with an adjustable fulcrum.

20 The invention also consists of certain parts and details and combinations of the same, as will be hereinafter fully described, and then pointed out in the claims.

Reference is to be had to the accompanying drawings, forming a part of this specification, in which similar letters of reference indicate corresponding parts in all the figures.

Figure 1 is a side elevation of the improvement with parts broken out. Fig. 2 is an enlarged transverse section of the same on the line $\alpha\alpha$ of Fig. 1. Fig. 3 is an enlarged side elevation of the bucket. Fig. 4 is an under side view of the same. Fig. 5 is an enlarged side elevation of part of the bucket-boom. Fig. 6 is an enlarged sectional side elevation of the lower end of the bucket on the line yy of Fig. 4, and Fig. 7 is a similar view of the same on the line zz of Fig. 4. Fig. 8 is a side elevation of part of the main carriage.

40 The improved hoisting-bucket G is provided with an inclined track B, on which is mounted to travel the main carriage C, on which is secured one end of a rope D, passing under a sheave E, supporting a U-shaped rod F, preferably connected at its ends with the sides of the bucket G. The rope D, after passing under the sheave E, extends upward and over a pulley H, mounted to turn in suitable bearings on the carriage C. The 45 rope D then extends above the track B and in line with the same to suitable hoisting

machinery for winding up or unwinding said rope.

On the outside of the bucket G is secured the boom I, provided on its under side with a rack I', meshing into the gear-wheel J, secured on a shaft J', mounted to turn in suitable bearings formed on the brackets K', extending downward from the tail-carriage K, rigidly connected by a reach K² with the main carriage C. The tail-carriage K travels in the rear of the main carriage C on the track B.

In order to hold the boom I in mesh with the gear-wheel J, two plates J² are held loosely on the shaft J', said plates extending on the sides of the boom I and held in place on the shaft by collars J⁴, secured by set-screws or other means on the said shaft J'. The upper ends of the plates J² are connected with each other by rollers J³, traveling on the tops of the boom J, so that the boom is free to pass between the two plates J², but at the same time is always held in mesh by its rack I' with the gear-wheel J. As the plates J² are fulcrumed loosely on the shaft J', the boom I is free to swing in any desired direction without being disconnected from the gear-wheel J.

On the reach K² is held to slide in a suitable bearing K³ a rod L, provided near the said bearing K³ with a lug L'. The other end of the rod L is rigidly connected with a lever N, operating the shaft O, mounted to turn in suitable bearings in the brackets K'. On the shaft O is fastened a crank-arm O', to which is secured one end of a brake-band P, passing around a brake-pulley P', secured on one end of the shaft J'. The other end of the brake-band P is secured on the bracket K', as is plainly illustrated in Fig. 1.

The lug L' of the rod L is operated on by the lower end of a lever Q, pivoted on a bumper R', supported by suitable brackets R on the track B. The upper end of the lever Q is connected with a rope Q' under the control of the operator. The bumper R' is provided in its top with a notch R², adapted to be engaged by the hook S' of a lever S, fulcrumed near the front end of the main carriage C. The lever S is provided with a downwardly-extending arm S², adapted to be

engaged by the sheave E, as hereinafter more fully described.

On the main carriage C is held to slide a rod S³, pivotally connected with one end of an arm S⁴, secured on the shaft S⁵, extending transversely and mounted to turn in suitable bearings on the main carriage C. The other end of the arm S⁴ is connected with a spring S⁶, held on the main carriage. In the middle of the shaft S⁵ is secured a hook S⁷, adapted to engage a hook E', formed on the sheave E, and serving to support the bucket G while the latter travels forward or backward with the main carriage C. On the rod S³ is a collar S⁸, serving to limit the rearward motion of the rod S³, caused by the spring S⁶.

The bucket G is provided with a hinged bottom G', on the under side of which is held in a suitable bearing G² a sliding bolt T, adapted to engage a bolt-plate G³, secured to the outside of the bucket G. The bolt T is pivotally connected with an arm T', pivoted on the under side of the bottom G', and is held in an outermost position by a spring T². (Plainly shown in Fig. 4.) The free end of the pivoted arm T' is pivotally connected with a rod T³, held to slide in a bearing G⁴, fastened on the under side of the bottom G'. The rod T³ projects slightly beyond the hinged end of the bucket-bottom G', and is pivotally connected with one arm of a bell-crank lever U, fulcrumed on the bucket G, and pivotally connected at its other end by a link U' with a bell-crank lever U², fulcrumed on one side of the boom I. The other arm of the bell-crank lever U² is pivotally connected by a link U³ with an arm U⁴, secured on a shaft U⁵, extending transversely and mounted to turn in suitable bearings on the under side of the boom I. A spring U⁶ is fastened by one end on one side of the boom I, and is connected at its other end with the link U³, so as to hold the latter in a normal position—that is, holding the sliding bolt T locked, as shown in Fig. 6. On one end of the shaft U⁵ is secured an arm U⁷ adapted to be engaged by a fixed lug at the end of the track B. When the bucket G is moving in the direction of the arrow a' to the end of the track B, the arm U⁷ strikes against the fixed lug, so that the said arm is moved in the direction of the arrow b', whereby the sliding bolt T is withdrawn from the bolt-plate G³ and the bottom G' is free to open—that is, to swing downward to permit the contents of the bucket G to drop out of the same. After the bucket has been emptied the bottom G' is again closed by the device now to be described. On the under side of the bottom G', near its hinged end, is secured an arm V, pivotally connected at its outer end with a link V', pivoted on a second link V², fastened on a short shaft V³, mounted to turn in suitable bearings on the top of the boom I, as is plainly shown in Fig. 3. Near the fulcrum end of the link V² is pivotally connected a rod V⁴, held to slide in a bearing V⁵, secured to the rear side of the boom I. A spring V⁶

is coiled on the said rod V⁴, and rests with one end against said bearing V⁵, and its other end presses against the front edge of the link V². The links V' and V² are prevented from closing too far inward toward the bucket G by a lug V⁷, secured on the said bucket opposite the joint of the two links V' and V². When the bottom G' is swung open, as previously described, the links V' and V² assume the position shown in dotted lines in Fig. 3, the spring V⁶ being then compressed. The moment the contents of the bucket G have passed out of the same the spring V⁶ forces the links V² and V' to their former position, so that the bottom G' is again closed. Then, as soon as the arm U⁷ is released from the fixed point by the bucket G moving in the inverse direction of the arrow a', the springs U⁶ and T² cause the sliding bolt T to again engage the bolt-plate G³, so that the bottom G' is again locked to the bucket G.

The operation is as follows: As shown in Fig. 1, the bucket G is on its return movement in the inverse direction of the arrow a'. As soon as the main carriage C strikes against the bumper R' the return motion ceases and the hook of the spring-pressed lever S engages the notch R² in the top of the bumper R'. At the same time the rod S³, moving against the bumper R', with the carriage, is pressed forward against the tension of the spring S⁶, so that the hook S⁷ swings rearwardly and disengages the hook E' of the sheave E. As the carriage C is locked in place on the bumper R' by lever S, the hook S⁷ remains in this position until the lever S is disengaged, as hereinafter described. The operator now causes the rope D to unwind, so that the sheave E is lowered, the bucket G swinging rearward and downward in the direction of the arrow c', the fulcrum being the contacting tooth of the rack I' with the gear-wheel J. The shaft J' is prevented from turning by the operator pulling on the rope Q', so that the lever Q presses against the lug L' of the rod L, whereby the latter presses the band P against the brake-pulley P', so as to prevent the shaft J' from turning. The boom I thus swings as a pendulum on the periphery of the gear-wheel J, and is held in contact with the said periphery by the plates J² and the rollers J³. When the boom I has assumed an upright position, as shown in dotted lines in Fig. 1, the operator releases his pull on the rope Q', so that the shaft J' is free to turn, and at the same time the rope D is permitted to unwind still farther, whereby the bucket G, with the boom I, passes downward until the bucket comes in contact with the article to be transferred. The bucket G is now in a horizontal position, and when the operator causes the rope D to wind up the bucket G is drawn forward and fills itself with the article to be transferred. A further winding up of the rope D raises the bucket G until the sheave E engages the under side of the arm S² of the spring-pressed lever S, so that the latter is

swung upward and is disengaged by its hook S' from the bumper R'. The rod S³ is now moved rearward by the action of the spring S⁶, so that the hook S' engages the hook E' of the 5 sheave E, and thereby supports the bucket G on the traveling motion of the carriage C. The carriage C, as well as the tail-carriage K, after being unlocked by lever S, as above described, is free to be pulled forward by further winding up of the rope D. This causes a 10 forward motion of the carriage C, the tail-carriage K, and all of the devices suspended from the same, so that the bucket G moves forward in the direction of the arrow a' to the 15 point where the bucket G is to be unlocked. When the carriage C, with the bucket G, arrives at the point of unlocking, the arm U⁷ strikes against the fixed point previously mentioned, the bucket G is emptied, the bottom G' is again locked, and the carriage is 20 returned, as previously described.

Having thus fully described my invention, I claim as new and desire to secure Letters Patent—

25 1. The combination, with a carriage provided with a tail-carriage, of a bucket held on a rope supported from the said carriage and a bucket-boom mounted on an adjustable fulcrum supported on the said tail-carriage, substantially as shown and described.

2. The combination, with a carriage provided with a tail-carriage, of a rope supported on one end of the said carriage and connected with a drum, a sheave held on the said rope, 35 a bucket supported from the said sheave, and a bucket-boom fastened on the said bucket and held to slide in a suitable bearing secured on the said tail-carriage, said bearing also forming a pivot for the said boom, substantially as shown and described.

3. The combination, with a carriage provided with a tail-carriage, of a rope supported on one end of the said carriage and connected with a drum, a sheave held on the said rope, 45 a bucket supported from the said sheave, a bucket-boom fastened on the said bucket and held to slide in a suitable bearing secured on the said tail-carriage, said bearing also forming a pivot for the said boom, and a lever 50 held on the said carriage and adapted to lock the latter in place, said lever being unlocked by the said sheave, substantially as shown and described.

4. In a hoisting-bucket, the combination, 55 with a bucket provided with a hinged bottom and locking devices for the same, of a spring mechanism for closing the bottom automatically after the load is dumped, said mechanism consisting of links V' V², jointed to a fixed 60 fulcrum at the upper end, to an offset from the hinged bottom at the lower end, and to each other in the middle, a spring for throwing these links toward alignment, and a stop for preventing them from passing into exact 65 alignment, substantially as shown and described.

5. The combination, with a carriage and a tail-carriage connected with the said carriage, of a bucket suspended from the said main carriage, a boom provided with a rack and 70 extending from the said bucket, a gear-wheel in mesh with the said rack, a shaft carrying the said gear-wheel and mounted in bearings on the said tail-carriage, side plates fulcrumed loosely on the said shaft, and rollers connecting 75 the said side plates with each other and resting on top of the said boom, substantially as shown and described.

6. The combination, with a carriage and a tail-carriage connected with the said carriage, 80 of a bucket suspended from the said main carriage, a boom provided with a rack and extending from the said bucket, a gear-wheel in mesh with the said rack, a shaft carrying the said gear-wheel and mounted in bearings 85 on the said tail-carriage, side plates fulcrumed loosely on the said shaft, rollers connecting the said side plates with each other and resting 90 on top of the said boom, a brake-pulley held on the said shaft, and a brake-band adapted to engage the said brake-pulley, substantially as shown and described.

7. The combination, with a carriage and a tail-carriage connected with the said carriage, of a bucket suspended from the said main 95 carriage, a boom provided with a rack and extending from the said bucket, a gear-wheel in mesh with the said rack, a shaft carrying the said gear-wheel and mounted in bearings on the said tail-carriage, side plates fulcrumed 100 loosely on the said shaft, rollers connecting the said side plates with each other and resting on top of the said boom, a brake-pulley held on the said shaft, a brake-band adapted to engage the said brake-pulley, and mechanism, 105 substantially as described, for operating the said brake-band, as set forth.

8. The combination, with a carriage and a tail-carriage connected with the said carriage, 110 of a bucket suspended from the main carriage, a boom provided with a rack and extended from the said bucket, a gear-wheel in mesh with the said rack, a shaft carrying the said gear-wheel and mounted in bearings on the said tail-carriage, side plates fulcrumed 115 loosely on the said shaft, rollers connecting the said plates with each other and resting on top of the said boom, a brake-pulley held on the said shaft, a brake-band adapted to engage the said brake-pulley, a lever for operating 120 said brake-band and held on the said tail-carriage, a rod connected with the said lever and mounted to slide on top of the said tail-carriage, and also provided with a lug, and a second lever under the control of the 125 operator and adapted to engage the lug of the said rod, substantially as shown and described.
